UNITED STATES PATENT OFFICE

ORA KRICHBAUM, OF DELAWARE, OHIO

INFLATABLE ARTICLE

Application filed March 14, 1930. Serial No. 435,778.

This invention relates to inflatable articles of the type comprising an envelope of impervious material and adapted to be inflated for use as a mattress or cushion, life preserver, canteen, hot water bottle or the like.

Inflatable mattresses or cushions heretofore developed have had a tendency to roll up or wrap around a person resting thereon, or to tip over with a person lying near the edge thereof. This unstable condition has been the source of inconvenience and annoyance, and it is therefore an object of the present invention to provide a device of this character which is stable or steady in use, and in which the tendency to tip over or roll up is materially decreased and generally eliminated.

Furthermore, prior devices of this character have required inflation to a comparatively high pressure, inasmuch as a low pressure inflation will not impart to the envelope any substantial rigidity, resulting in bulging of the envelope at one portion when weight is applied to another portion. The higher pressure inflation in turn decreases the desired cushion effect. It is therefore an object of the present invention to provide an inflatable envelope of the character described, which may be inflated to a comparatively low pressure, and yet avoid the undesirable bulging referred to above.

Another object of the invention is to provide a method of manufacturing an inflatable envelope, whereby the convenience and economy of production thereof may be materially increased.

Still another object of the invention is to provide an inflatable envelope with securing means at the marginal portions thereof, whereby regions near spaced corners of the envelope may be secured together to permit the device to be used as a weather-protective cape or poncho, without in any way altering its utility as an inflatable article.

Other objects and features of novelty will be apparent from the following description and the accompanying drawing, in which

Figure 1 is a perspective view of an inflatable article according to one embodiment of

the present invention, the form shown being a mattress or cushion.

Figure 2 is a cross section taken along the line 2—2 of Fig. 1.

Figure 3 is a partial diagrammatic plan of a portion of the device in an early stage of its construction.

Figure 4 is a view similar to Fig. 3, and showing the device in a later stage of construction.

Figure 5 is a partial plan view showing one form of the completed device, illustrating the communication between the various compartments formed during the manufacture, and

Figure 6 is a perspective view of the device when used as a weather protective garment.

Referring more particularly to the drawing which illustrates the following description of one embodiment of the present invention, the completed article is illustrated in Figs. 1, 2 and 6. The article is indicated generally at 10, and comprises an upper wall 11 and a lower wall 12. The embodiment shown is of ribbed construction, in that the outer surface comprises a plurality of longitudinally extending ribs or bulges 13, separated by longitudinally extending grooves 14.

The upper and lower walls 11 and 12 are secured together at their margins 15, and a tube 16 extends through one corner of the margin to connect with the interior air compartments, and is provided with a valve 17 for retaining the air therein when the same has been inflated.

As shown in Fig. 1, securing means 18 are provided, which may be eyelets to receive lacing, glove fasteners, buckles or practically any form of securing device. These securing devices are preferably carried by the margin 15 adjacent the opposite ends of one edge thereof, but may be otherwise located in spaced relation, and are adapted to be secured together to bring the envelope into a substantially conical form, such as shown in Fig. 6, so that the same may be used as a weather protective garment, in the nature of a poncho or cape. The advantages of this arrangement will be readily apparent, inasmuch as pneumatic mattresses, such as illustrated in

Fig. 1, are particularly desirable for camping, and substantially all forms of outdoor activities. The popularity of inflatable mattresses is largely due to their adaptability 5 for storage in a comparatively small space, resulting in ready portability. Hence, as by nature, the mattress is intended to be carried about, it is very desirable to give the same utility as a weather protective garment, as 10 the same will be available whenever desired. Also, the envelope may be partially inflated, so as to insulate the body, or may be filled with hot water for added warmth. Furthermore, when filled with cold water, it may serve 15 as a canteen for drinking water.

Referring now to Fig. 2, it will be noted that the bulges 13 and grooves 14 in the upper wall 11 are respectively staggered with respect to those of the lower wall 12. This is 20 brought about by the manner of attachment of elongated internal strips or webs 19 which are secured at their side edges to the upper and lower walls 11 and 12 respectively. The upper line of attachment of each web is off 25 set laterally from its lower line of attachment, thereby giving the webs inclined positions. The upper and lower walls being secured together along their margins, it will be apparent that any tendency for the webs 19 to assume 30 a vertical position when the envelope is inflated will be successfully combated, the margin joints at the ends of the cushion being particularly effective to produce this result. This diagonal or inclined disposition of the 35 internal webs 19 produces staggered grooves 14 in the upper and lower walls when the envelope is inflated. The arrangement described is of particular importance, as it prevents the undesirable tendency to rolling hereinbefore 40 referred to. It also avoids a column effect of the webs, which would otherwise cause hard ridges when compressed in use. Furthermore, this arrangement contributes to the distribution of stresses which permits the low 45 pressure inflation without localized bulging.

The webs 19 do not extend the full length of the envelope, but terminate short of the ends thereof, as shown in Fig. 5, thus leaving a passage around the end of each web and 50 permitting intercommunication between the compartments 20 formed by the bulges 13 and the webs 19. It should be noted that one side of one margin of each of the webs 19 is secured, as at 21, to the respective ridges 14 55 of the lower wall 12, and that the opposite side of the opposite margin of each of the webs 19 is secured, as at 22', to the opposite side of a ridge 14 of the upper wall 11.

While the compartments 20 are connected 60 as shown in Fig. 5, undesirable bulging of the envelope 10 is nevertheless prevented by the webs 19, inasmuch as the tendency to bulge is taken by the strength of the web. The stresses are distributed over the cumulative 65 areas of the several strips, and thus any local-

ized bulging is avoided, and at the same time all of the flexibility and comfort of low pressure inflation is preserved. A very steady and comfortable mattress or cushion is thus provided.

The article described above may be very economically manufactured by the following method:

A sheet of flexible material 11, preferably 75 impervious, such as rubber or rubberized fabric, but which may be cloth, composition, or other treated fabric, is spread over a suitable supporting surface, and a separator sheet 23 is spread thereover. The sheet 23 is preferably 80 paper or similar material, and is provided with lines of apertures 24, so that the separator 85 23 is in the nature of a stencil sheet. Preferably liquid adhesive material or rubber cement is spread over the sheet 23 in the region of the apertures 24, so that the adhesive material will cover the areas of the sheet 11 exposed by the apertures, but the adhesive may be omitted in some instances, as will be later explained.

Strips 19 of flexible material such as cloth, 90 composition, rubber, or rubberized or other treated fabric are then applied over the sheet 23 and spaced so that the respective margins 26 of the strips 19 overlie the lines of apertures 24. Thus the material of the strips 19 95 contacts with the material of the sheets 11 through the line of apertures 24, and is secured thereto by the adhesive material when the same is employed.

A second separator sheet 27 is applied over 100 the structure shown in Fig. 3, and is provided with lines of apertures 28, which are disposed so as to overlie the opposite margins 29 of the respective strips 19. Adhesive material is preferably again applied in the manner already described, and a sheet 12, 105 similar to the sheet 11, is applied over the sheet 27. It will be readily apparent that the sheets 11 and 12 are respectively secured to the opposite margins of the strips 19, 110 through the apertures of the respective separator sheets 23 and 27.

To form an envelope such as illustrated 115 in Fig. 1, the separator sheets 23 and 27 are of equal area, which is slightly smaller than the area of the sheets 11 and 12. The sheets 23 and 27 are therefore centered with respect to the other sheets, thus leaving contacting margins of the sheets 11 and 12, which will 120 adhere to form the margin 15.

It should also be noted that the line of apertures 24 in the sheet 23 is spaced from the margin thereof and from the sheet 11, a distance greater than the spacing of the line of apertures 28 from the corresponding margin of the separator sheet 27. This spacing is, of course, necessary in order to provide the 125 staggered attachment for the strips 19, as shown in Fig. 2, and resulting in the improved operation of the cushion, but the same 130

does not offer any difficulty in the manufacture, inasmuch as the sheets 23 and 27 may be identical, and manufactured in great quantities, it being only necessary to reverse the sheet 27 with respect to the sheet 23 and the desired spacing will be thereby taken care of.

In lieu of the rubber cement above described, the desired securing may be arrived at by merely vulcanizing the device assembled as shown in Fig. 4, when rubber or rubberized fabric is used for the sheets 11 and 12. The surfaces contacting through the apertures in the separator sheets will adhere together by virtue of the vulcanizing process, so that the adhesive material may be omitted. However, even when vulcanizing is contemplated it is desirable to employ a light adhesive, such as benzol, for coating portions of the separator sheets adjacent their apertures, and thus stenciling adhesive onto the rubber surfaces exposed thereby.

Various grades of paper used to construct the separator sheets 23 and 27 will, of course, act differently, depending upon which grade is employed and also depending upon whether or not a vulcanizing step is employed. Furthermore, it is within the purview of the invention to employ a material analogous to paper, but which will disintegrate and substantially disappear in the vulcanizing process. It is, therefore, obvious that variation in result will be provided by the character of material employed in the construction of the separator sheets.

However, with several types of paper, the same will merely adhere to the inner wall of the sheets 11 and 12, being vulcanized to such inner walls and substantially embedded therein, thus forming a paper lining for the compartments 20.

Referring again to Figure 3, the separator sheets 23 and 27 may be of two ply paper, or such paper as will split into two sheets when the surfaces thereof respectively adhere to the walls of the envelope, and the same is expanded. This arrangement will result in a complete paper lining for the internal wall of each of the compartments 20. The same result may be accomplished by

using two identical apertured separator sheets at 23 and two more at 27, or by providing an individual apertured separator sheet for each side of each strip 19. This may be done by cementing a large suitably apertured separator sheet to each side of a flexible sheet, and cutting up the same into strips to form the strips 19 before assembly thereof as described.

Aside from the separating or stenciling use during the manufacture, this paper lining will be of protective utility for the completed cushion in use. As the envelope may be exposed to some heat where collapsed, the paper lining will prevent such heat from causing the walls to stick together.

While the preferred embodiment of the invention has been illustrated and described in such detail as to enable any one skilled in the art to practice the invention, nevertheless the scope of the invention is not to be limited to any of the details disclosed, but instead includes such embodiments of the broad idea as fall within the scope of the appended claim, it being obvious that various modifications and changes may be resorted to without departing from the spirit of the invention.

Having thus described my invention what I claim is:

An inflatable envelope comprising upper and lower walls of flexible air-tight sheet material directly connected together at their edges, and a series of webs connecting said walls arranged in substantially parallel planes inclined transversely to their length when the envelope is inflated, said envelope when deflated having substantially parallel walls lying close together and said webs lying between said walls in substantially parallel arrangement therewith, said envelope having fastening means positioned along one side thereof adjacent the corners, by means of which the deflated envelope may be used as a cape with two corners fastened together across the chest of the wearer.

In testimony whereof, I hereunto affix my signature.

ORA KRICHBAUM.
